UNITED STATES PATENT OFFICE

1,992,036

ELECTRIC CIRCUIT BREAKER

Raymond J. Meier, Stonehurst Hills, Pa., assignor to General Electric Company, a corporation of New York

Application September 7, 1933, Serial No. 688,474

4 Claims. (Cl. 200—166)

My invention relates to electric circuit breakers, more particularly to arc interrupting contact structure of circuit breakers of the liquid-break or oil type.

5 The use of so-called finger contacts for stationary contact structure of oil circuit breakers, for example, may involve, under certain conditions, burning of the contacts when the circuit breaker is closed on heavy currents. In general, finger contacts comprise a pair of opposed contact members or plates resiliently mounted and biased towards each other so as resiliently to engage at opposite sides thereof a wedge-shaped movable contact member, commonly known as the bridging contact. The finger contacts are initially engaged at the free or outer ends thereof and spread apart by the bridging member during the circuit closing operation. In the event, however, that the aforesaid oil immersed contacts are closed on 10 heavy current, contact at the point of initial engagement may result in a certain degree of arcing and consequent generation of gas between the contact tips. The gas pressure so formed tends to blow apart the finger contacts so as momentarily 15 to separate the same from the bridging member and cause further arcing and generation of high gas pressure within the circuit breaker. This condition is very undesirable since not only are the contacts burned and sometimes damaged by arcing but the performance of the circuit breaker is 20 less efficient.

A principal object of my invention is the provision of improved finger contact structure for oil circuit breakers and the like which shall substantially eliminate arcing and burning upon closure of the contacts on heavy currents and which shall be simple and rugged in construction and efficient and reliable in operation.

My invention will be more fully set forth in the 40 following description referring to the accompanying drawing, and the features of novelty which characterize my invention will be pointed out with particularity in the claims annexed to and forming a part of this specification.

45 Referring to the drawing, Fig. 1 is an elevational, fragmentary view of one pole of an oil circuit breaker embodying the present invention; Fig. 2 is an enlarged end view of the circuit breaker contact structure shown in Fig. 1 in the open circuit position; Fig. 3 is a similar view showing the contact structure in closed circuit position, and Fig. 4 is an enlarged detailed view of a portion of the contact structure shown in the preceding figures.

50 In Fig. 1 is partially shown one pole of an oil

circuit breaker comprising stationary contact structure 1 and a coacting movable contact or bridging member 2 arranged to bridge and interconnect the stationary contact structure of two similar poles. The aforesaid contact structure is immersed and coacts in a suitable insulating liquid 3, such as oil, operation of the circuit breaker between open and closed circuit positions being effected by vertical movement of lift rod 4.

The stationary contact structure is of the well known finger type, and comprises the main current-carrying contacts 5 and the arcing contacts 6, the final contact separation and the initial contact engagement taking place between the arcing contact 6 and the bridging contact 2 for reasons well known in the art. The function of the contacts 5 is to carry the current traversing the circuit breaker when it is normally closed and the construction of the current-carrying contacts may assume any suitable form as for example that disclosed and claimed in Tobey et al. Patent 1,752,127, granted March 25, 1930 for "Electric switch".

The arc interrupting contacts 6, referring to Fig. 2, comprise a pair of opposed contact plates or fingers 7 resiliently biased towards each other and supported by semi-rigid leaf springs 8. The main supporting means for the contact structure comprises an adapter 9 suitably secured, as by the clamping means 10, to the lower end of the current lead-in conductor stud 11 of the circuit breaker. The lower end of the adapter 9 is provided with a depending positioning block 12 at the opposite sides of which are clamped the supporting and conducting means for the finger contacts 7.

The current-carrying connections between the adapter 9 and the contacts 7 comprise flexible copper strips 13 which are clamped at their lower ends between the corresponding contacts 7 and members 14 secured as by riveting to the finger contacts. The upper ends of the conductors 13, together with the contact supports 8, are clamped to opposite sides of the adapter extension 12 between the plate members 15. The finger contact construction so far described is well known in the art and is generally similar to the construction disclosed and claimed in Thumin Patent 1,787,291 granted December 30, 1930 for "Electric switch".

In Fig. 2 the contact structure is illustrated in the open circuit position, the closing operation involving vertical, upward movement of the wedge-like bridging member 2 and the consequent spreading apart of the finger contact members as illustrated by Fig. 3. The wedge-like member 2

makes initial point contact with the lower extremities or arcing tips 7' of the finger contacts prior to spreading apart of the contacts and it is at this initial stage of contact engagement that 5 burning of the contacts and arcing may result when the contacts are closed against heavy currents. If the initial arcing is severe the finger contacts 7 may be momentarily blown apart by reason of the resulting arc pressure, thereby causing 10 extensive arcing between the finger contacts and the member 2. When the contacts are closed under such conditions they may be badly burned or damaged. Moreover, the high gas pressures generated within the circuit breaker tank are 15 very undesirable.

For the purpose of substantially eliminating burning or arcing upon initial engagement of the contacts when closed against heavy currents, means are provided for applying pressure to the 20 points of initial contact engagement and for shifting said pressure upon complete closure of the contacts. To this end a pair of substantially rigid members 16 are supported by and pivotally mounted in the plates 15, as best illustrated by Fig. 25 4, the lower end of each member 16 being turned inwardly, as at 16', so as to engage at its tip a corresponding finger contact 7. A pair of leaf springs 17 clamped at the upper ends thereof to the adapter assembly by the plates 18 are arranged 30 to engage the members 16 and resiliently bias the same towards each other into engagement with the contact fingers 7 as illustrated in Fig. 2.

The aforesaid adapter assembly including the conductors 13, supports 8, mounting plates 15, 35 leaf spring 17 and clamping plates 18 is suitably clamped together to form a single structure as by through-bolts 20.

The pivoted support for each member 16, referring to Fig. 4, comprises simply a T-shaped 40 notch 21 formed at the lower edge of a supporting plate 15 into which is fitted a correspondingly shaped extension 22 of the member 16. The member 16 is, therefore, free to pivot about its support, the extension 22 being held in place by 45 the support 8 on one side and by the leaf spring 17 on the opposite side when the adapter assembly is bolted in position.

The operation of the contact structure is as follows. When the movable bridging member 2 initially engages the arcing tips 7' closing the circuit the leaf springs 17, through the pivoted rigid members 16, serve to concentrate pressure at the arcing tips 7' where initial contact occurs. Accordingly, the coacting contact surfaces make 55 firm contact at a definite pressure, which in itself reduces contact resistance and minimizes burning. The tendency of the finger contacts to blow apart in case of slight arcing is likewise opposed by the concentration of pressure at the arcing tips.

60 As the member 2 continues the closing movement after the initial contact engagement, the finger contacts 7 are gradually spread apart with the result that the lower tips 16' of the members 16 are moved out of engagement with the arcing portions 7'.

When the contacts are completely closed, as 70 illustrated in Fig. 3, it is desirable that pressure be applied to the finger contacts, as at the mid-portions thereof, so that they will properly align themselves with respect to the coacting flat surfaces of the bridging member and make uniform contact engagement therewith. During spreading of the contacts 7, the members 16 are engaged by pins 23 rigidly mounted on the finger contacts 75 at substantially the mid-portions thereof and

loosely engaged by the supports 8 for facilitating alignment of the contacts. Accordingly, the pressure exerted by the leaf springs 17 is transferred from the arcing tips 7' to the pins 23 for biasing the finger contacts into uniform contact engagement with the sides of the member 2 in the desired manner. This shifting of the pressure is made possible by the relation between the pivotal movement of the members 16 and the combined transverse and angular movement of 10 the finger contacts due to engagement by the wedge-like contact member 2.

It will, therefore, be noted that pressure is applied to the arcing tips 7' of the finger contacts both during engagement and separation of the 15 contacts for reducing burning upon closure against heavy currents and for substantially limiting arcing at the tips 7' upon opening of the contacts. During normal closed circuit position, however, the pressure is applied to the finger contacts in the desired manner so as to insure proper alignment and uniform contact engagement.

It should be understood that my invention is not limited to specific details of construction and arrangement thereof herein illustrated, and that 25 changes and modifications may occur to one skilled in the art without departing from the spirit of my invention.

What I claim as new and desire to secure by Letters Patent of the United States, is:

1. An electric circuit breaker comprising a movable contact member, a pair of relatively stationary opposed finger contact members adapted to engage said movable member at opposite sides thereof in the closed circuit position, means normally biasing said finger contacts into uniform contact engagement with said contact member in the closed circuit position, means other than the aforesaid means applying pressure to the tip of each of said finger contact members substantially at the point of initial engagement with said movable member so as to increase the contact pressure at said point, and means causing shifting of said pressure from said point in response to closing movement of the contacts so that said pressure is applied uniformly to bias said finger contact into engagement with said movable member.

2. An electric circuit breaker comprising a wedge-like contact member, a pair of opposed finger contact members adapted to engage said wedge-like member at opposite sides thereof in the closed circuit position, a stationary adapter for supporting said finger contact members, a pair of members pivotally mounted with respect to said adapter arranged to engage the free ends of said finger contact members respectively, a pair of leaf springs fixed with respect to said adapter and resiliently biasing each of said pivoted members towards said finger contact members, said pivoted members arranged so as to urge the tips of said finger contact members into high pressure contact engagement with said wedge-like member at the points of initial and final contact engagement, and means carried by said finger contact members causing the bias of said leaf springs to be applied adjacent the mid-portions of said finger contact members in response to closing movement of the contacts.

3. An electric circuit breaker comprising a pair of opposed finger contact members, a movable contact adapted to engage and spread apart said finger members so as to be engaged thereby at opposite sides in the closed circuit position, a spring for applying pressure to the tip of each

- finger member during initial engagement thereof with said movable contact, a second spring for biasing each finger contact into uniform contact engagement with said movable contact, said second spring acting substantially at the mid-portion of the finger contact, and means for shifting the pressure from said tips to adjacent the mid-portions of said finger members upon complete closure of said contacts.
- 10 4. An electric circuit breaker comprising a fixed adapter, a pair of opposed finger contact members electrically connected to said adapter, means secured to said adapter for supporting and biasing towards each other said contact members, a
- 15 movable contact member arranged to engage and

spread apart said finger contacts against said bias in the closed circuit position, a rigid member co-acting with each finger contact pivotally carried by said adapter, resilient means arranged to bias each rigid member into engagement with the extremity of said finger contact during the initial closing and final opening operations, said rigid member being moved out of engagement with the extremity of said finger contact during the circuit closing operation, and means for applying the bias 10 of said last-named resilient means to urge said finger contacts into uniform contact engagement with said movable contact in the closed circuit position.
